C. M. SLICK.

LICENSE TAG OR SIGN PLATE,
APPLICATION FILED FEB. 19, 1917.

1,241,292.

Patented Sept. 25, 1917.

UNITED STATES PATENT OFFICE.

CHARLES M. SLICK, OF HAGERSTOWN, MARYLAND.

LICENSE-TAG OR SIGN-PLATE.

1,241,292.

Specification of Letters Patent. Patented Sept. 25, 1917.

Application filed February 19, 1917. Serial No. 149,502.

To all whom it may concern:

Be it known that I, CHARLES M. SLICK, a citizen of the United States, residing at Hagerstown, in the county of Washington and State of Maryland, have invented certain new and useful Improvements in License-Tags or Sign-Plates, of which the following is a specification, reference being had therein to the accompanying drawing.

10 This invention relates to a license tag or sign plate especially designed for the use of automobileists, the primary object of the invention being to provide a construction of tag which may be applied to a light box 15 illuminated in any preferred manner, to serve both as a day light and night indicator.

A further object of the invention is to provide a license tag or sign plate, which 20 may be issued in place of the ordinary sign plate by State or other authorities and which bears the license numerals or other indicating matter in a properly perforated form, so that the figures themselves as viewed from 25 the face of the plate will form a daytime sign, while the perforations therein will permit light to shine through the figures of the plate to outline the same, and thus form an illuminated sign for use at night.

30 A still further object of the invention is to provide a sign plate having a novel construction of perforated figures adapting the plate for efficient use as both a day and a night signal, and whereby a cheaply constructed, as well as a new and ornamental type of plate is produced.

A still further object of the invention is to provide a license plate which may be employed as a closure for the open front of a light box carrying a red danger light or bull's-eye together with an electric lamp or other illuminating means which will serve to illuminate both the sign plate and red light or bull's-eye.

The invention consists of the features of construction, combination and arrangement of parts hereinafter fully described and claimed, reference being had to the accompanying drawing, in which:

35 Figure 1 is a front elevation of a light box provided with my improved license tag or sign plate.

Fig. 2 is a top plan view of the same.

Fig. 3 is a vertical front to rear section on 40 the line 3—3 of Fig. 1.

Fig. 4 is a horizontal transverse section

through the sign plate on the line 4—4 of Fig. 1.

Referring to the drawing, 1 designates my improved license tag or sign plate, which is 60 preferably made of sheet metal, and may be, as usual, of oblong rectangular form. As shown, this tag or sign plate is provided with letters or characters 2, forming the sign matter, which may be in the nature of 65 a suitable number, the name or abbreviation of a State or community, and suitable figures denoting the time of issue, or the period for which such license tag or sign plate is valid.

70 As shown in the present instance, the sign plate 1 is of proper form to form a closure for the open front of a sign box or casing 3, comprising a body portion of a general form corresponding to that of the sign plate and 75 having a top or extension 4 of suitable form provided with a bull's-eye or tail light lens 5, which may be of red or other suitable colored glass fitted within a suitable holder. The sign plate is adapted to fit within suitable guide grooves 6 at the bottom and sides of the casing and to be held in position by the walls of these grooves. An incandescent electric lamp 7 or other suitable illuminating agent is provided for illuminating the interior of the lamp box. This light is designed to shine through the slots of the figures 2 as well as through the bull's-eye 5, to serve the double purpose of displaying the license number and giving the usual rear 80 light indication for night service.

85 In accordance with my invention, each letter or figure 2 of the sign matter upon the sign plate 1 is of novel construction, and comprises a central portion or panel 8 and a perforated marginal portion 9. The panel 8 forms the ground or field of the character and is preferably flat or plane-surfaced so that it may be painted or suitably colored in contrast to the sign plate, to provide a 100 clearly defined figure. In practice, this field or ground portion may be either cameo, intaglio or plane, that is, disposed in the plane of the plate itself, the last named arrangement being shown in the present instance, while the perforated margin 9 is stamped out in the form of a marginal embossing.

105 By reference to Figs. 3 and 4, the form of each sign letter will be readily understood, 110 and it will be seen that the marginal portion 9 is stamped out so as to provide spaced

relatively converging walls 10 forming a light emitting slot or perforation 11, the said walls 10 being connected and reinforced at intervals by cross pieces or braces 12. 5 These cross pieces or braces hold the walls in proper relation and support the field portion or panel in position, and may be arranged at any desired intervals apart. It will be seen that as the walls 10 converge 10 outwardly, the inner portions of the slots or perforations are of maximum width and thus provide for the ready passage of the light rays, and that as said slots flare and are contracted outwardly the light rays are 15 concentrated at the point of emission and thus form a clearly defined light border around the center field or panel. Hence the unilluminated sign plate will present a distinctive character of sign matter for day indication, and will also provide an illuminated type of sign matter of a distinctive character for night indication. 20 It will be observed that inasmuch as the sign plates are simple in construction, they 25 may be manufactured at a cost but slightly exceeding the cost of other sign plates, and will be of greater value and convenience on account of their adaptability for both day and night use. By employing a light box of 30 simple construction, such as of the form disclosed, the sign plates may be mounted upon

and as a part of the casing of the usual tail lamp, so that a tail light may be produced and the sign plate illuminated in a most effective manner from the same source of 35 light.

Having described my invention, I claim:

1. A license tag or plate comprising a plate of sheet material bearing sign matter thereon, said sign matter embodying characters each consisting of a painted ground or field portion and a marginal portion, said marginal portion being embossed or struck out from the plate and comprising spaced walls connected at intervals by cross pieces, 40 45 said walls extending outwardly on relatively converging lines.
2. A license tag or plate comprising a plate of sheet material bearing sign matter thereon, said sign matter embodying characters each consisting of a painted ground or field portion and a perforated marginal portion, said marginal portion being embossed or struck out from the plate and comprising spaced walls connected at intervals by cross pieces. 50 55

In testimony whereof I hereunto affix my signature in the presence of two witnesses.

CHARLES M. SLICK.
